[57] CLAIM

The ornamental design for a combined fabric measuring and cost computing device, substantially as shown.

DESCRIPTION

FIG. 1 is a top plan view of a combined fabric measuring and cost computing device showing our new design; FIG. 2 is a front side elevational view thereof, the rear side being a mirror image thereto;

FIG. 3 is a bottom plan view thereof;

FIG. 4 is a left end elevational view thereof;

FIG. 5 is a right end elevational view thereof;

FIG. 6 is a bottom plan view of another embodiment of our new design of FIGS. 1-5;

FIG. 7 is a left end elevational view thereof;

FIG. 8 is a right end elevational view thereof.
